(57) **CLAIM**

The ornamental design for an indoor/outdoor audio speaker, as shown and described.

DESCRIPTION

FIG. 1 is a perspective view of my new indoor/outdoor audio speaker design;

FIG. 2 is a front elevational view thereof;

FIG. 3 is a left side elevational view thereof, the right side elevational view thereof being a mirror image;

FIG. 4 is a rear elevational view thereof;

FIG. 5 is a top plan view thereof;

FIG. 6 is a bottom plan view thereof; and,

FIG. 7 is a cross-sectional view taken on line 7—7 of FIG. 2.

The features of the indoor/outdoor audio speaker shown in broken lines are for illustrative purposes only and form no part of the claimed design.
